UNITED STATES PATENT OFFICE.

JULES L. CADDELL, OF MAXTON, NORTH CAROLINA.

PLOW.

1,233,751.

Specification of Letters Patent. Patented July 17, 1917.

Application filed November 10, 1916. Serial No. 130,609.

To all whom it may concern:

Be it known that I, JULES L. CADDELL, a citizen of the United States, residing at Maxton, in the county of Robeson and State of North Carolina, have invented a new and useful Plow, of which the following is a specification.

This invention relates to plows and one of its objects is to provide a plow in which 10 the stock can be readily adjusted to hold the plow at any desired angle relative to the ground.

A further object is to provide a novel 15 form of plow beam which is simple, durable and inexpensive in construction and serves not only as a means for properly holding the stock in any position to which it may be adjusted, but also as means for securely holding the handles.

20 With the foregoing and other objects in view which will appear as the description proceeds, the invention resides in the combination and arrangement of parts and in the details of construction hereinafter described 25 and claimed, it being understood that changes in the precise embodiment of the invention herein disclosed, can be made within the scope of what is claimed, without departing from the spirit of the invention.

30 In the accompanying drawings the preferred form of the invention has been shown.

In said drawings:—

Figure 1 is a side elevation of the plow, a portion thereof being shown in section.

35 Fig. 2 is a plan view thereof.

Fig. 3 is a section on line 3—3 of Fig. 1.

Referring to the figures by characters of reference 1 designates a beam formed of a heavy strip of metal, this beam being formed 40 at its forward end with a hook 2 for engagement with the draft means. The rear end of the beam is curved downwardly and then extended forwardly as shown at 3 and formed within the upper edge of the beam 1 45 above the forward end of the under portion 3 is a longitudinal series of notches 4. A stock 5 in the form of an elongated metal loop, straddles the beam 1 and the under portion 3 and is pivotally connected to the

50 forward end of said portion 3, as shown at 6. The lower end of the stock straddles and is pivotally connected, as at 7, to the forward end of a shoe 8 and the rear end of this shoe is connected by a link 9 to the 55 rear or curved portion of the beam. Straddling the upper portion of the stock 5 and

pivotaly connected to it as at 10 is the forked lower end of a lever 11. This lever has a bracket 12 in which is slidably mounted a spring pressed dog 13, said dog being 60 adapted to be elevated against the action of the spring by a hand lever 14 pivotally mounted on the lever 11. The dog 13 is normally seated in any one of the recesses 4 and when thus positioned holds the stock 65 4 and when thus positioned holds the stock 65 against movement about its pivot 6.

Connected to the under portion 3 of the beam 1 by a bolt 15 are the lower forward ends of handles 16, these handles diverging rearwardly and upwardly and being attached as at 17, to ears 18 provided at the outer ends of a cross bar 19. This bar has an intermediate loop 20 which straddles the beam 1 and is adjustably connected thereto by a bolt 21 extending through any one of 75 a series of apertures 22 formed in the beam. As the bolt 21 is located out of line with the pivot 17 it will be apparent that by swinging the loop 20 about said pivot the bolt 21 can be brought to position to enter 80 any one of the apertures 22 and thus hold the handles 16 at different angles. It is of course to be understood that the ears 18 are loosely mounted on the bolt or pivot 17 so as to permit angular adjustment of the 85 loop 20.

Obviously by means of the lever 11 the stock 5 can be adjusted angularly so as to bring the point of the plow to any desired angle. This adjustment will not affect the 90 relative positions of the plow and the shoe 8, however.

What is claimed is:—

1. A plow including a beam having a downwardly turned portion extended forwardly, a stock pivoted on the forward end of the under portion of the beam and straddling the upper portion thereof, a shoe pivotally connected to the lower end of the stock, a link connection between the rear end 95 of the shoe and the downturned portion of the beam, and coöperating means upon the upper portion of the stock and the beam for holding the stock against movement about its fulcrum. 100

2. A plow including a beam having a downwardly turned portion extended forwardly, a stock pivoted on the forward end of the under portion of the beam and straddling the upper portion thereof, a shoe pivotally connected to the lower end of the stock, a link connection between the rear 110

end of the shoe and the downturned portion of the beam, a lever connected to the upper end of the stock, a dog carried thereby, and means for actuating the dog, there being 5 a series of recesses in the beam any one of which is adapted to receive the dog.

3. A plow including a beam having a downwardly turned portion extended forwardly, a stock pivoted on the forward end 10 of the under portion of the beam and straddling the upper portion thereof, a shoe pivotally connected to the lower end of the stock, a link connection between the rear end of the shoe and the downturned portion of 15 the beam, coöperating means upon the upper

portion of the stock and the beam for holding the stock against movement about its fulcrum, upwardly and rearwardly diverging handles connected to the under portion of the beam, a cross bar connected to said handles, said bar having an intermediate loop straddling the beam, and an adjustable connection between said loop and the beam. 20

In testimony that I claim the foregoing 25 as my own, I have hereto affixed my signature in the presence of two witnesses.

JULES L. CADDELL.
